UNITED STATES PATENT OFFICE.

WALTER C. MOORHEAD, OF SENECAVILLE, OHIO, ASSIGNOR OF ONE-HALF
TO OLIVER O. EBERLY, OF SENECAVILLE, OHIO.

BIT.

SPECIFICATION forming part of Letters Patent No. 736,998, dated August 25, 1903.

Application filed December 12, 1902. Serial No. 135,001. (No model.)

To all whom it may concern:

Be it known that I, WALTER C. MOORHEAD, a citizen of the United States, residing at Senecaville, in the county of Guernsey, State of Ohio, have invented certain new and useful Improvements in Bits; and I do hereby declare the following to be a full, clear, and exact description of the invention, such as will enable others skilled in the art to which it appertains to make and use the same.

This invention relates to bits for mining-machines; and it has for its object to provide a bit which will be less worn in the cutting operation than the ordinary chisel-shaped bit usually employed and in the operation of which bit there will be less energy required.

A further object of the invention is to provide a bit which may be easily and quickly dressed.

In the drawings forming a portion of this specification, and in which like numerals of reference indicate similar parts in both views, Figure 1 is a perspective view showing a bit embodying the present invention. Fig. 2 is a side elevation of the bit.

Referring now to the drawings, there is shown a bit comprising a transversely-rectangular stem 5, at one end of which is formed a cutting-point 6, said cutting point or blade being in the form of a rectangular pyramid the axis of which intersects the axis of the stem at an obtuse angle, while the side faces of the blade are at obtuse angles to the corresponding side faces of the stems. At the points of meeting of the sides of the stem and the corresponding side faces of the blade the faces of the bit are rounded, as illustrated.

In the use of the present bit it is secured in the mining-machine in the same manner as the usual chisel-shaped bit, and the machine

is operated in the usual manner. Owing to the particular shape of the blade of the bit it enters the coal more readily than the chisel-shaped bit, and thus requires less energy to operate it, and it is found in practice that it does not dull so quickly and that it is more easily and quickly dressed, so that its use is more economical.

The present bit comprises a cutting edge at each side of the upper face of its blade and at the broadest portion of the blade, so that in drawing the blade upwardly through the coal there is a minimum tendency to wedging of the blade, this arrangement of the two cutting edges being distinguished from a structure in which a pyramidal blade is disposed with an edge in the middle of the upper side of the blade, so that the axes of the stem and blade lie in a plane diagonal to the stem and blade, and I claim no part of such arrangement as my invention.

What is claimed is—

A bit for mining-machines, consisting of a stem and a blade, the stem being rectangular in cross-section and the blade having the shape of a square pyramid, the axis of which lies at an obtuse angle to the axis of the stem, the axes of the stem and blade lying in a plane which intersects the upper and lower faces of the stem and blade at right angles, and the blade presenting a single cutting edge at each side of its upper face, which cutting edges converge to the point of the blade.

In testimony whereof I affix my signature in presence of two witnesses.

WALTER C. MOORHEAD.
